UNITED STATES PATENT OFFICE.

WARWICK HENRY BEANES, OF LONDON, ENGLAND, ASSIGNOR TO BAKER-PERKINS COMPANY INCORPORATED, OF WHITE PLAINS, NEW YORK.

OVEN.

Application filed August 22, 1925, Serial No. 51,846, and in Great Britain June 12, 1925.

This invention relates to ovens for bread baking and similar purposes, and of the well known Perkins or closed steam tube type, and has for its object to provide improved means for varying the quantity of heat supplied to different parts of the oven from its fire-box or furnace or furnaces.

The invention comprises the employment with the oven, of a fire-box or furnace or furnaces in which heat is generated in any convenient manner, and adapted to be varied in position relatively to the oven or to the tubes employed for the transmission to the oven of the heat so generated.

Referring to the two accompanying sheets of explanatory drawings:—

Figure 1 is a sectional elevation, Figure 2 a sectional plan and Figure 3 a sectional end view of an oven fire-box as constructed and arranged in one convenient manner in accordance with this invention and provided with a grate for the burning of solid fuel.

Figure 4 is a plan showing the arrangement of the tubes projecting above the said fire-box.

The same reference letters in the different views indicate the same or similar parts.

The fire-box *a* is, as shown in the illustrations, mounted on balls *b* supported on tracks *c* and thus made portable relatively to the oven *d* or adapted to be readily varied in position relatively to the oven or to the steam tubes of the same.

The said tubes, which may be either of the circuit or of the stopped end type, are disposed in groups in any known manner to convey heat to various parts of the oven baking chamber, portions of all the tubes in the respective groups being arranged for subjection to the heat from the fire-box. Thus in the example illustrated the tubes *e* in one group are arranged for the heating of the lower part of the baking chamber (of which a portion is shown at *f*, Figure 1) whilst the tubes *e'* in the other group heat the upper portion of the said chamber. Or, in other words, the tubes *e* impart the bottom heat and the tubes *e'* the top heat to the loaves or goods in the baking chamber *f*.

The quantity of heat supplied to the respective groups is varied by a movement of the fire-box *a* relatively to the portions of the

respective tube groups *e* and *e'* projecting into the space or area *g* above the said box, the said area forming part of the furnace 55 chamber containing such box. The permissible extent of said movement may be such as to concentrate the heating upon either of the respective tube groups or to distribute the heating over both or all the groups in 60 any desired ratio. In the position of the fire-box *a* indicated by full lines at Figure 1, the said box is at the limit of its movement to the right at which position the heating is concentrated, on the tube group *e'*. The 65 dotted lines indicate the extreme left hand position of the fire-box at which the heating is concentrated on the tube group *e*. At the said position of the fire-box between such extremes, both groups of tubes will be subjected to the direct heat from the fire-box *a* beneath them.

The movement of the fire-box or furnace or furnaces may be in a longitudinal, transverse or other direction relatively to the 75 oven or baking chamber for variation of the distribution amongst the respective tube groups.

Having thus described my invention what I claim as new and desire to secure by 80 Letters Patent is:—

1. In ovens, the combination comprising a baking chamber, a plurality of groups of closed steam tubes having portions projecting within said chamber, a furnace, and 85 means whereby the heat from said furnace may be concentrated upon either of said tube groups or distributed in varying proportions over all of them.

2. In ovens, the combination comprising 90 a baking chamber, a furnace chamber, a plurality of groups of closed steam tubes projecting into both the said chambers, the projections of the respective groups in the furnace chamber entering said chamber from 95 opposite sides of the same, and a fire-box so movable within the furnace chamber that the heat therefrom may be concentrated upon either of the tube groups or distributed in varying proportions over all of them.

3. In ovens, the combination comprising 100 a baking chamber, a furnace chamber, a plurality of groups of closed steam tubes projecting into both the said chambers, the

projections of the respective groups in the furnace chamber entering said chamber from opposite sides of same, a fire-box, tracks for supporting said fire-box within said furnace chamber, and rolling elements between the fire-box and said tracks enabling said box to be moved along said tracks and the

heat therefrom concentrated upon either of the tube groups or distributed in varying proportions over all of them.

In testimony whereof I have signed my name to this specification.

WARWICK HENRY BEANES.
